FORCE FEED OILCAN

Gustave Lidseen, Chicago, Ill.

Application April 29, 1943, Serial No. 484,994

8 Claims. (Cl. 221—51)

This invention relates to a force feed oil can of the type in which an oil forcing plunger in the base part of a nozzle structure is operated by manipulation of a lever on the can for the ejection of oil.

In oil can structure, as for example such as disclosed in my Patent No. 1,542,896, dated June 23, 1925, complete pumping structure is utilized including an oil feed pipe extending from the cylinder in the spout structure to the bottom of the can and with an inlet check valve therein and with the cylinder provided with an outlet valve, and, with such complete pump structure, upon operation thereof by the manipulation of a pump lever on the can, oil may be pumped through the spout during any position of the can.

An important object of my present invention is to simplify the construction and reduce the cost of manufacture of the can by eliminating parts, such as the inlet pipe and valve, and providing a cylinder in the spout structure which can be readily filled by tilting of the can and from which, by manipulation of a lever on the can, oil may be ejected through the spout in any position of the can.

A further object of the invention is to provide a cylinder space in the base of the spout structure with a plunger therefor controlled by an actuating rod axially shiftable by the manipulation of a lever on the can and with the arrangement such that, upon manual depression of the lever, the movement of the rod may be rapidly accelerated for quick movement of the plunger for spurt ejection of oil from the cylinder and out of the spout.

A further important object is to provide improved packing arrangement for the plunger actuating rod with the arrangement such that, after each return of the can operating lever, the lever will engage with packing structure to force packing material intimately against the rod to thus prevent leakage of oil from the can container to the exterior along the rod.

A can structure embodying the various features of my invention are disclosed on the accompanying drawing in which:

Figure 1 is a side elevation of the can structure;

Figure 2 is an enlarged plan view thereof;

Figure 3 is an enlarged section on plane III—III, Figure 2;

Figure 4 is an enlarged section on plane IV—IV, Figure 2, with the actuating lever in normal position; and

Figure 5 is a section view similar to Figure 4,

but showing the operating lever depressed for shift of the plunger and ejection of oil through the spout structure.

The can shown comprises a cover 10 having flange segments 11 for interlocking with flange segments 12 on the can body or container 13 to hold the edge of the container against a gasket 14 on the cover so as to form a tight seal when the cover is applied. The cover is of sheet metal and has the extension 15 thereon forming the base part of the spout structure, the spout tip 16 being secured in the neck part 17 of the extension 15. The extension 15 provides the cylinder space 18 for the cup shaped plunger 19. The bottom wall of the plunger has the inlet passageway 20, the metal of the bottom around the opening being upset to provide the depending flange 21 and the upstanding inclined valve seat flange 22. A check valve 23, shown in the form of a ball, normally engages the seat 22 to close the passageway 20, the ball being operable within a cage 24 which at its lower end is held in place by the seat flange 22.

At one side of the cover extension 15, a guide bushing 25 is mounted on the cover and secured thereto as by riveting as indicated at 26. Slidably axially in this bushing is the plunger actuating rod 27 which, at its lower end, extends through the opening 28 in the U-shaped bracket 29, the rod being intimately engaged by the outer leg 30 of the bracket to hold the bracket in horizontal position, and notches 31 in the rod receiving a split washer 32 on which the bracket seats. The inner leg 33 of the bracket has ears 34 and 35 extending therefrom and having their upper ends rounded to engage the plunger along the opposite sides of the depending flange 21 of the plunger so that, when the rod 27 is raised, the plunger will be shifted up in the cylinder space 18, a spring 36 resisting upward movement of the plunger.

Extending across the can top 10 is the operating lever 37 which has the substantially elliptical opening 38 therethrough for receiving the cover extension 15. A stiffening and strengthening flange 39 extends downwardly from the operating lever at its edges, and, adjacent to the lever opening 38, the flange is extended downwardly to provide abutment ears 40 and 41 at diametrically opposite sides of the extension 15 and in engagement therewith, the lower edges of the ears engaging the cover 10.

The end 42 of the lever 37 deflects or inclines downwardly for engagement by the thumb or finger of the can operator. The other end of the

lever extends over the bushing 25 and has the opening 43 therethrough for receiving the upper end of the rod 27 which terminates in a head 44 above the lever so that when the lever is rotated by pressure on the finger end 42 thereof, the rod 27 and the bracket 29 thereon will be raised for upward shift of the plunger in the cylinder. When the operating lever is released, the spring 36 will shift the plunger down against the bracket 29 for return of the rod to its normal position with its head against the lever 37. To prevent leakage of oil from the container to the exterior thereof along the rod 27, packing material 45 is provided and held in place on the outer end of the bushing by a sheet metal cap 46 which frictionally engages the bushing, the outer end of the cap being frusto-conical so that upon downward pressure thereon the packing material will be forced radially into intimate engagement with the rod. The packing cap forms a stop for the operating lever 37 when the lever is swung back to normal position upon downward shift of the rod 27 by the force of the spring 36 so that, after each release of the operating lever, the lever will tap the packing cap to shift the cap down against the packing to take up any looseness of the packing and thus keep the packing intimately in engagement with the rod to prevent oil leakage.

As the lever 37 receives the extension 15 through its opening 38, the axis X of rotation of the lever is substantially in the vertical plane of the minor axis of the opening. The ears 40 and 41 of the lever have longitudinally extended fulcrum edges for engagement with the cover to the right of the axis X, the distance of these surfaces from the axis X increasing toward the rear ends of these surfaces, as clearly shown on Figure 3. With this arrangement, when pressure is exerted on the end 42 of the operating lever, the lever will be rotated on its axis X, the ears 40 being swung forwardly with the lever to bring their fulcrum edges 47 progressively into engagement with the cover 10 resulting in raising of the lever at its axis while it is being rotated. This rotary and bodily movement of the lever is limited by the engagement of the outer edge of the lever opening 38 with the extension 15, as shown on Figure 5, the rounded heels 48 of the fulcrum edges being then in engagement with the cover.

The can body may be provided with a handle, but for manipulation of the can a handle would not be necessary for the operator may grasp the can body or container in the hand and with one of his fingers operate the lever 37. Owing to the inclined end 42 of the lever, pressure thereon will have a vertical downward component, and a radial inward component toward the lever axis. As the lever is being swung down by the finger, the radial pressure component will increase whereby the heels 48 of the fulcrum edges will be quickly moved toward the vertical line of the axis X for accelerated movement of the plunger in cylinder 18. Furthermore, as the lever is being rocked by the operator, the distance between the forward end of the lever and the point of engagement of the fulcrum edges with the cover increases, and the distance between the finger engaged end of the lever from this point correspondingly decreases so that the outer end of the lever is further accelerated in its movement for shift of the plunger into the cylinder. When the can is to be used, it is first tilted sufficiently for unseating of the valve ball 23 for flow of oil from the can body into the cylinder 18 and then, when the lever 37 is operated, the shift of the plunger in

the cylinder will exert pressure on the oil for discharge from the cylinder out through the spout tip 16, the accelerated movement of the outer end of the lever in the manner explained exerting accelerating pressure against the oil in the cylinder for rapid or spurt discharge from the spout.

When the cylinder 18 has been filled, the can may be operated in its normal or vertical position by manipulation of the lever 37 for forced ejection of oil from the spout, the force of gravity and the pressure in the cylinder then holding the valve ball 23 closed. The can may be used in inverted position for natural or gravity flow of oil from the can body through the cylinder and spout, or, by operating the lever while the can is inverted or tilted, spurt pressure may be applied, the resistance of flow through the more or less restricted spout tip causing sufficient pressure in the cylinder, when the plunger is operated, to hold the valve ball 23 seated against the force of gravity.

I have thus produced a force feed oil can of simple and economically manufactured and assembled parts which may be easily operated for forced feed of oil from the can container in any position of the can and without the need of a feed pipe extending to the bottom of the container. All the operating parts are mounted on the cover structure which can therefore be readily applied to can containers of various capacity.

I have shown a practical and efficient embodiment of the features of my invention, but I do not desire to be limited to the exact construction, arrangement and operation shown and described as changed and modifications may be made without departing from the scope of the invention.

I claim as my invention:

1. An oil can comprising a container, a spout structure extending from the top of said container with its base portion defining a cylinder, a plunger shiftable in said cylinder and having an inlet for flow of oil from the container to the cylinder, a check valve for said inlet, an operating lever on the container top having an opening therethrough for receiving the base of the spout structure to be guided thereby for rotational movement, said lever being manually engageable at one end for rotational movement thereof, a connection between the other end of said lever and said plunger, ears depending from opposite sides of said lever and having longitudinally extended fulcrum edges for engagement with the container top, said fulcrum edges being of increasing distance from the rotation axis of said lever in the direction of the manipulated end of the lever whereby upon manipulation of the lever it will have combined rotary and bodily upward movement for accelerated movement of said plunger for forced feed of oil from said cylinder through the spout structure.

2. An oil can comprising a container, a spout structure extending from the top of said container with its base portion forming a cylinder, a plunger in said cylinder having an inlet for flow of oil from the container into the cylinder, a check valve for said inlet, a spring resisting inward movement of the plunger, an operating lever on the container top having an opening therethrough receiving said spout structure to be guided thereby for rotation, one end of said lever being adapted for manual engagement for rotation thereof, a connection from the other end of said lever to said plunger for inward shift of the plunger when the lever is manually rotated, ears depending from the opposite sides of said lever

for fulcrum engagement with the container top at points between the manipulated end of said lever and the vertical line of the rotation axis of said lever whereby upon manipulation of said lever it will be given combined rotary movement and upward bodily movement for accelerated movement of said plunger in said cylinder for forced feed of oil through the spout structure.

3. An oil can comprising a container, a spout structure extending from the top of said container, a cylinder space in said spout structure, a plunger operable in said cylinder space, an inlet for flow of oil from the container into said cylinder, a check valve controlling said inlet, a bushing on the container top, an operating rod shiftable axially in said bushing, a connection between the inner end of said rod and said plunger whereby upon outward shift of said rod said plunger will be shifted for discharge of oil through the spout structure from said cylinder, a spring for returning said plunger and said connection, an operating lever on said cover connected with the outer end of said operating rod for shifting said rod outwardly for operation of the plunger, packing surrounding said operating rod above said bushing, a cap frictionally engaging said bushing and having a frusto-conical end engaging said packing whereby upon downward movement of said cap said packing will be pressed against said rod, said cap forming a stop for said lever whereby upon return of said plunger and connection by said spring upon release of said lever, said lever will strike said cap for movement of said cap to force said packing against said rod.

4. An oil can comprising a container and a top therefor, an extension on said top defining a cylinder, a discharge outlet from said cylinder, a plunger movable in said cylinder, an oil inlet for said cylinder and a check valve therefor, a lever fulcrumed on said top, a rod connected at its outer end with one end of said lever and having connection at its inner end with said plunger whereby upon manipulation of said lever said rod will be shifted for movement of said plunger for discharge of oil through the cylinder outlet, spring means for returning said lever and rod and plunger upon release of said lever, a guide bushing on said top for said rod, a cap for said bushing and packing material therein for compression against the rod when the cap is moved down on the bushing, said cap upon return of said lever being engaged by the lever for shift of the cap to take up any wear or loosening of the packing whereby to keep the bushing sealed against leakage therethrough of oil from the container.

5. An oil can comprising a container having a cover with an extension thereon forming a cylinder having a discharge outlet, an oil inlet for said cylinder and a check valve therefor, a plunger in said cylinder, a connection from said plunger to the exterior of said cover, a lever on said cover connected at one end to the outer end of said connection and having an opening for receiving said extension whereby to limit the longitudinal movement of said lever but to permit rotational movement thereof, the other end of said lever being manually engageable for rotation of the

lever, a support extending from said lever and having cam engagement at its lower edge with said cover in such manner that when said lever is manipulated it will be rotated and coincidentally raised for accelerated movement of said connection and the plunger in said cylinder for forced feed of oil from the cylinder outlet.

6. An oil can comprising a container, a spout structure extending from the top of said container with its base defining a cylinder, a plunger operable in said cylinder, an inlet for flow of oil into the cylinder, an operating lever supported on the container top for rotational movement, a connection between one end of said lever and said plunger, said lever at its other end being manually engageable for rotation thereof, a fulcrum support depending from said lever and having cam engagement with the container top in such manner that when the lever is manipulated for rotation thereof its rotation axis will be coincidentally raised to cause accelerated movement of said plunger by said connection for accelerated forced discharge of oil through said spout structure.

7. An oil can comprising a container, a spout structure extending from the top of the container with its base portion defining a cylinder, a plunger operable in said cylinder, an operating lever extending across the top of the container, a connection between one end of said lever and said plunger, guide flanges on said lever depending therefrom at opposite sides of said cylinder and engaging at their lower edges against the top of the container to form a fulcrum support for the lever, the other end of said lever being manually engageable for rotation thereof on said fulcrum support, the edges of said fulcrum flanges having cam engagement with the cover in such manner that when the lever is rotated it will be coincidentally bodily raised for accelerated movement of said connection and the plunger in the cylinder for forced feed of oil from the spout.

8. An oil can comprising a container and a spout structure extending therefrom, ejection means associated with said spout for ejection of oil therethrough, a bushing on the container top, an operating rod shiftable axially in said bushing, a connection between the inner end of said rod and said ejection means whereby upon outward shift of said rod said ejection means will be operated for discharge of oil through the spout structure, a spring for returning said ejection means and connection, an operating lever on said cover connected with the outer end of said operating rod for shifting said rod outwardly for operation of said ejecting means, packing surrounding said operating rod above said bushing, a cap frictionally engaging said bushing to hold said packing pressed against said rod, said cap forming a stop for said lever whereby upon return of said ejecting means and said rod by said spring upon release of said lever, said lever will strike the cap for movement of the cap on the bushing to take up any loosening or wear of the packing whereby to seal the bushing against leakage therethrough of oil from the container.

GUSTAVE LIDSEEN.
